COTTON PICKER

Filed Nov. 25, 1938

UNITED STATES PATENT OFFICE

2,247,686

COTTON PICKER

Edward A. Johnston, Chicago, Ill., assignor to International Harvester Company, a corporation of New Jersey

Application November 25, 1938, Serial No. 242,238

4 Claims. (Cl. 56—44)

This invention relates to cotton pickers. More particularly it relates to improvements in doffing mechanism.

In the rotating spindle type of cotton picker, one of the problems is to remove the picked cotton from the spindles efficiently and without excessive twisting of the cotton. By the construction of conical spindles, as shown in my United States Patent No. 1,888,506, dated November 22, 1932, doffing has been greatly facilitated, particularly by arranging the spindles at an axis with respect to the carrying drum whereby the upper edges of the spindles move in a plane which can be engaged by a doffer to provide a substantial doffing area in the nature of a planar surface. To further improve the doffing in cotton pickers of the spindle type, constructions have been devised as disclosed and claimed in my Patent No. 2,140,631, dated December 20, 1938. In such constructions the spindles are arranged on carriers whereby they may be brought into the doffing area at angles approaching a tangent, to facilitate doffing from the large to the small end of each individual spindle.

The principal object of the present invention is to provide further improvements in a conical spindle type of cotton picker as above referred to.

A further object is to provide spindles having the teeth thereon arranged and presented during operation to the doffer so as to facilitate the doffing operation.

The above objects are accomplished by providing spiral teeth arranged in a direction on the rotating spindles so as to be continually presented during operation to the doffer substantially at a tangent to the doffing element.

A preferred embodiment of the means for accomplishing the objects of this invention is shown in the drawing, in which:

Figure 1 is a plan view of a portion of a cotton picker, broken away in section to show the relative positions of the spindles with respect to one of the doffing elements;

Figure 2 is an enlarged view of one type of spindle;

Figure 3 is an enlarged view of a modified type of spindle; and,

Figure 4 is an elevation of a portion of a spindle-carrying bar, showing also in section a portion of a doffer in its relative position with respect to the picking spindles.

In order to limit the drawing to show only the essential features of applicant's improved cotton picker construction, only such portions of

a drum structure and a doffer structure have been shown as are necessary to clearly illustrate the construction and functioning of the device. Cotton pickers of the type having a rotating drum or other supporting means on which spindle bars are carried are well known in the art. Attention is called particularly to my allowed application above referred to, which discloses such construction. The drum structure is rotatably mounted on a supporting structure and moved along the field with the rotating spindles, which are driven by suitable power means, brought into engagement with the plant and subsequently brought into engagement with the doffer, which is also driven by suitable power means.

In the drawing, a portion 10 of the drum structure is shown in section to illustrate somewhat diagrammatically the cam track 11, in which a number of ball bearing assemblies 12 are visible. Said assemblies are mounted on the upper ends of arms 13 rigidly secured to and serving as extensions for vertical spindle bars 14. Said bars have bearing surfaces 15 at their upper ends and are adapted to be supported and operated as shown in the construction of the allowed application. A driving gear 16 is shown in mesh with a gear 17, which drives a vertical shaft for operating the rotating spindles 18 on each of the spindle bars 14. Each of the spindles 18 is mounted at an angle with respect to the spindle bar on which it is mounted, being held in position with a movable member 19 threaded into the spindle bar. It will be noted that the spindles are inclined or arranged at such an angle that one edge of the spindle at all times lies in a plane perpendicular to the axis of the spindle bar. Said spindle bars, it will be understood, are mounted on the drum structure 10, which is rotatable on a vertical axis M. As the axes of the bar 14 are parallel to the axis M. of the drum structure, it can be said that one edge of each spindle 18 at all times lies in a plane perpendicular to the axis of the drum structure.

The teeth on the drawings of Figures 1 and 4 are shown somewhat diagrammatically. Said teeth are arranged on spirals around the spindles, converging somewhat from the base to the outer end of smaller diameter. The drum structure is rotated in the direction shown by the arrow adjacent the axis M. The spindles are rotated during operation in the direction shown by the arrows at the bases of the spindles.

Figure 2 shows a preferred type of spindle. Spirally arranged teeth 20 are located in spiral grooves 21. The teeth project upwardly and are

shaped to engage and pick a maximum amount of cotton with a minimum amount of leaves and without injuring the stalks and branches of the cotton plants. The smooth portions of the spindles 22 between the grooves 21 provide a contact surface which engages the stalks of the plants to prevent injury thereto.

In Figure 3 a modified type of spindle of a more aggressive nature is shown. The teeth 20 are arranged on the surface of the spindle and 10 project upwardly above the smooth portions 22 between the spiral rows of teeth.

A portion of the doffer construction is illustrated in the drawing. A doffer shaft 23 is positioned on a vertical axis parallel to the axis M of the drum structure. Said shaft is splined to receive a plurality of doffer members 24. Each of said members carries a doffing element 25 providing a plurality of doffing surfaces, which describe an annular planar doffing area during rotation of the shaft 23. The doffer construction is arranged so that the doffing elements 25 lie closely adjacent to or lightly engage the edges of the spindles 18, which lie in a plane. It will be understood that the corresponding spindles on each of the bars 14 are arranged in circumferential rows such that each spindle successively approaches and passes through the doffing area.

In order to facilitate doffing, the spindles are arranged on the oscillating bars whereby each bar may be angled as the spindles approach the doffing area to angle the spindles into trailing position with respect to the direction of rotation of the drum structure. The spindles are then brought into somewhat of a tangential relation with respect to the doffer element, as best shown by the lowermost spindle shown in Figure 1. With the doffer element moving in the direction indicated by the arrow in Figure 1, the doffing element engages the spindle at some point upwardly from its end and sweeps downwardly toward the lower end, thereby acting to push the cotton fibers wound around the spindle outwardly to a section of the spindle having a smaller diameter. This loosens the tightly wound cotton and facilitates its removal from the spindle. The teeth 20 are arranged so as to repeatedly release the cotton when pressure is exerted on the cotton toward the outer end of the spindle.

Due to the necessity for a large number of spindles and to other mechanical limitations, it is not possible to move the spindles through the entire doffing area in tangential relation with respect to the doffing element. The principal feature of this invention is to provide a spindle construction which aids materially in doffing by improving the relative relation between the teeth of the spindles and the doffer. By arranging the teeth in spirals as shown, it will be understood that, during rotation of the drum structure on the axis M, bodily advancing the spindles and simultaneously rotating the spindles in the angular direction indicated by the arrows thereon, the teeth are brought upwardly into doffing position as the spindles are bodily advanced. As the angle of the teeth is approximately thirty (30) degrees with respect to the axis of the spindles, the tangential position is improved by this angle. This improvement assures that, during a substantial portion of the doffing period and throughout a substantial portion of the doffing area, the doffing elements sweep downwardly along the teeth from the base

of the spindle toward the outer end substantially parallel to the rows of teeth.

The spindle construction shown in Figure 2 is particularly designed for a doffer of the type illustrated. The doffing element 25 is formed of a resilient material, such as rubber. In a submerged tooth construction, as shown in Figure 2, the spindle engaging portions of the doffing element may rest directly on the portions 22 of the spindle without engaging the teeth 20, which would tend to cause excessive wear of the doffing elements. During operation, the elements resting on the smooth portions 22 sweep down the spindle substantially parallel to the rows of teeth 20, removing the cotton therefrom effectively without actual contact with the teeth.

The operation of the improved cotton picker construction has been explained above in connection with the description of the drawing. As pointed out, only such elements have been shown as are necessary to clearly illustrate the principle of the invention and the means necessary to effectively accomplish the desired results. Applicant contemplates the use of the structure shown on any cotton picker on which it could be satisfactorily applied. Applicant also contemplates as a portion of his invention any modifications falling within the scope of the appended claims.

What is claimed is:

1. In a cotton picker having rotatable conical picking spindles, means for bodily moving said spindles through a doffing area, said spindles being tilted at an angle such that one edge of each moves through a plane, said spindle being formed with steep spiral rows of teeth, said rows being at a small angle with respect to the axis of the spindles, and a circular rotatable doffer element arranged with the doffing surface in a plane at right angles to the axis of rotation, said doffing element being rotatable in a direction such that the doffing surface moves in a direction opposite to the bodily movement of the spindle, said spindle being rotated in a direction with the surface adjacent the doffing element moving in the same direction as said element, the direction of the spirals of said teeth being such that adjacent teeth of a row by rotation of the spindle are brought into contact with the doffing element 50 moving successively from the outer end towards the base and substantially parallel to the row.
2. In a cotton picker having a vertical rotatable drum structure, vertical bars mounted for oscillation on said structure, picking spindles rotatably mounted on said bars in circumferential, spaced rows around the drum structure, and doffing elements rotatable to provide planar doffing areas above each row of spindles, said spindles being conical and being mounted at an angle on the vertical bars, whereby their edges pass through the planar doffing surface in contact with the doffing elements, said spindles being provided with spiral rows of teeth, the spirals being arranged with respect to the direction of rotation of the spindles such that successive teeth are brought into doffing position from the small end of the spindle towards the base, whereby the doffer successively engages teeth on portions of larger diameter on the spindles, and said rows 60 also being at a steep angle whereby oscillation of the bars to bring the spindles into the doffing area at an angle thereto brings the spirals into tangential relation with respect to the doffing elements.
3. In a cotton picker, a rotating drum struc-

ture, a plurality of rotatable spindles carried by said structure, said spindles being arranged at an angle with respect to the axis of the drum structure whereby the doffing edges of the spindles lie in planes at right angles to the axis of the drum structure, doffing elements mounted for rotation on an axis parallel to the axis of the drum structure said elements defining an annular doffing area during rotation, said spindles being provided with a plurality of teeth arranged in steep spiral rows therearound, said rows being at a small angle with respect to the axis of the spindle whereby the spindles are brought into doffing area with the rows of teeth generally tangential to the doffing elements and whereby due to the steep angle of the teeth on the spindles doffing takes place over a substantial portion of the doffing area with the doffing elements moving downwardly from the bases of the spindles to the ends thereof substantially parallel to the rows of teeth.

4. In a cotton picker, a rotating drum structure, a plurality of spindle supporting members mounted on axes parallel to the drum axis on said structure, a plurality of rotatable spindles car-

ried by said members, said spindles being arranged at an angle with respect to the axis of the drum structure whereby the doffing edges of the spindles lie in planes at right angles to the axis of the drum structure, doffing elements mounted for rotation on an axis parallel to the axis of the drum structure said elements defining an annular doffing area during rotation, said spindles being provided with a plurality of teeth arranged in steep spiral rows therearound, said rows being at a small angle with respect to the axis of the spindle, means for oscillating the spindle supporting members to angle the picking spindles with respect to the radii of the drum structure as the spindles approach the doffing area whereby the spindles are brought into said area generally tangential to the doffing elements and whereby due to the steep angle of the teeth on the spindles doffing takes place over a substantial portion of the doffing area with the doffing elements moving downwardly from the bases of the spindles to the ends thereof substantially parallel to the rows of teeth.
